UNITED STATES PATENT OFFICE.

ALBERT R. THOMPSON, OF SAN JOSE, CALIFORNIA, ASSIGNOR TO ANDERSON-BARNGROVER MFG. CO., OF SAN JOSE, CALIFORNIA, A CORPORATION OF CALIFORNIA.

PRESSURE-COOKER.

1,210,563.

Specification of Letters Patent. Patented Jan. 2, 1917.

Application filed July 26, 1916. Serial No. 111,476.

To all whom it may concern:

Be it known that I, ALBERT R. THOMPSON, a citizen of the United States, residing at San Jose, in the county of Santa Clara and State of California, have invented certain new and useful Improvements in Pressure-Cookers, of which the following is a specification.

My invention relates to a cooker for sealed cans containing food products and the like, wherein the cans and the material contained therein are subjected to steam under pressure for a given length of time. In devices of this type it is necessary, in order to maintain the desired pressure within the cooking chamber and to prevent the escape of steam therefrom, to provide means for introducing the cans into said chamber, and for removing them therefrom, in such a manner that at no time will there be established a direct communication between said chamber and the outside air. In order to accomplish this result, I make use of a valve constituting an improved form of the package-handling valve for steam-tight chambers, for which United States Letters Patent No. 1,188,581, dated June 27, 1916, were granted upon my application. It is also highly desirable, in cookers of the type described, to provide means for positively and accurately feeding the cans into the entrance and exit valves, and for removing said cans therefrom, instead of depending upon gravity alone for moving the cans. This I accomplish in the present device by automatic feed and discharge mechanism which will be hereinafter fully described.

Referring to the accompanying drawings—Figure 1 is a side elevation, broken, of my cooker, certain parts being in partial section. Fig. 2 is a part sectional end elevation, enlarged, viewed from the left end, the sectioned part being on the line 2—2 of Fig. 1. Fig. 3 is a part sectional end elevation, enlarged, viewed from the right end, the sectioned part being on the line 3—3 of Fig. 1. Fig. 4 is an elevation of the initial feed wheel 14 exposed in its drum 13. Fig. 5 is a sectional detail, enlarged, on the line 5—5 of Fig. 1. Fig. 6 is a top view of the cam 65, which controls the outlet valve with respect to the presence or absence of a can. Figs. 7, 8, 9 and 10 are diagrammatic views showing the operation of the inlet valve which is also the operation of the outlet

valve when a can is present. Fig. 11 is a diagrammatic view showing the first operation of the outlet valve when no can is present.

In the drawings, the reference numeral 1 designates the shell or barrel, constituting the cooking chamber, which is here shown as of cylindrical form, closed at its ends by means of suitable end plates 2, and supported upon legs 3. The barrel 1 is to be supplied with steam under pressure, but as this is well known in cookers of the pressure type, I have not deemed it necessary to show the steam connections. Also with regard to the can-path or course of the cans through the barrel or cooking chamber, the form I herein partially show in Fig. 2 is that now well known, as, for example, that shown in Letters Patent of the United States No. 1,172,501, dated Feby. 22, 1916, granted upon my application, and comprising an outer fixed helically directed rail 4 of T-section the leg 5 of said rail extending inwardly, and an inner rotatable reel or drum member 6, mounted on a shaft 7 and carrying an annular series of angle-rails 8 parallel with the axis of the reel. By the rotation of the reel member 6, the cans lying between the helically directed rail 4 and the annular series of rails 8 are carried throughout the cooking chamber in the manner common to cookers of this type.

The shaft 7 carrying the reel or drum member 6 is suitably journaled in the end plates 2, with appropriate means, not illustrated, for preventing the escape of steam, and projects outwardly beyond said end plates. One of said projecting ends carries a worm wheel 9, Figs. 1 and 2, which meshes with and is driven by a worm indicated at 10 in Fig. 2, fixed upon a transverse drive shaft 11 carrying a drive pulley 11', Fig. 1.

The cans containing the material to be cooked are fed into the barrel by the mechanism seen in elevation at the left in Fig. 1 and in detail in Figs. 2, 4 and 5, and which comprises the following parts: A chute 12 successively delivers the cans, in a horizontal position, to a substantially cylindrical drum 13, within which is an initial feed wheel 14, carried by a short horizontal shaft 15, and intermittently rotated by means of a Geneva mechanism 16 and 17, best seen in Figs. 2 and 5, the two members thereof being mounted respectively upon the shaft 110

2. **BEST AVAILABLE COP, 210,563**

15 and a continuously rotating shaft 18. This shaft 18, through the gears 19 and 20, Fig. 5, drives a cam shaft 21, and is itself driven by a main drive shaft 11 by means of 5 a train of bevel gears 22, 23 and 24, a vertical shaft 25, and a pair of bevel gears 26 and 27, the latter being mounted on the shaft 18, all as seen in Fig. 1.

The feed wheel 14, which as seen in Fig. 5, 10 is best made double, has a series of peripheral depressions 14', each adapted to receive a can, to advance the same within the drum 13, and to deliver it, in the proper timed relation, into the can inlet valve. The delivery of the can is positively effected by means 15 of a fixed finger 13'—Figs. 4 and 5, which lies between the double members of the feed wheel 14. The can inlet valve is essentially similar to the package handling valve for 20 steam-tight chambers, for which United States Letters Patent No. 1,188,581, were issued, as above mentioned, and comprises a cylinder 28, Figs. 1, 2 and 4, having a can inlet port 29 communicating with the feed 25 wheel drum 13, Fig. 4, and a can outlet port 30, out of line with said can inlet port, and communicating with a second feed-wheel shell 31, as seen in Fig. 2. A pair of oppositely disposed steam-tight pistons 32 and 30 32', which are indicated in Figs. 7 to 10, are slidably mounted within said cylinder 28, and are operated, through connecting rods 33 and 33', by levers 34 and 34', fulcrumed respectively at 35 and 35', and carrying cam 35 following rollers adapted to lie within and follow groove cams 36 and 36', the latter being fixed upon a main horizontal cam shaft 37 driven by the bevel gear 23. To understand the operation of this valve, reference must be had to Figs. 7 to 10. The 40 pistons 32 and 32', actuated by the above described mechanism, are spaced apart when at the right hand limit of their travel, as seen in Fig. 7, to allow a can to be interposed between them, in a horizontal position, by the intermittent feed wheel 14. Said pistons then move to the left, as in Fig. 8, with the can between them, until said can is brought into registry with the outlet port 50 30, the inlet port 29 being covered by the piston 32 before the outlet port 30 is uncovered by the piston 32'. After the can is discharged through the outlet port 30, the piston 32' approaches the piston 32, as in Fig. 9, thereby forcing the steam contained therebetween back through said outlet port into feed wheel casing 31 and the barrel of the cooker, to prevent any loss or waste of steam. The two pistons then travel, in close 55 relation, to the right until the can outlet port is entirely covered by the piston 32', after which they separate and assume their spaced positions, as in Fig. 10, in readiness to receive another can.

60 65 To insure prompt and positive removal of

the can from the steam-tight valve, I have provided an ejector rod 38, Figs. 1 and 2, slidably mounted in a bracket 39 and extending, as shown in Fig. 2, into the piston valve-cylinder 28, through a suitable steam-tight packing gland 40, at right angles to the axis of said cylinder and opposite the can outlet port 30. The ejector rod is operated, at the proper time, by a lever 41, Fig. 2, fulcrumed at 42, and carrying a cam following roller 43 adapted to lie within and follow a groove cam 44 carried upon the shaft 21. The can is thus forced by the ejector 38 out of the valve and into the feed-wheel shell 31, and is caught within one of the pockets 45', Fig. 2, of a feed wheel 45. This feed wheel is carried upon a horizontal shaft 46, which is continuously driven by means of a pair of gears 47 and 48, Fig. 1, the latter being fixed upon the projecting right hand end of the main drum shaft 7. This continuously rotating feed wheel 45 carries the can around, in the direction of the arrow in Fig. 2, and delivers it into the barrel of the cooker and between the helically directed rail 4 and the annular series of rails 8 of the drum 6, which rails, as before stated, constitute the can-path.

At the discharge end of the machine is a discharge wheel 51, Fig. 3, mounted upon the continuously driven shaft 46, and enclosed by a shell 52. Said wheel is formed with peripheral recesses 51', each adapted to receive a can from the can-path rails 8 of the drum 6 and convey the same out of the barrel 1 and into a steam-tight discharge valve, the action of said wheel being similar to that of the feed wheel at the inlet end of the cooking chamber. Said discharge wheel is composed of two similar disks, one only being shown in Fig. 3, spaced apart sufficiently to permit a swinging discharge finger 53 to operate between them. Said finger is fulcrumed at 54, and carries at its lower end a cam following roller 55, adapted to lie within and follow a groove 56, formed in a cam member 57 fixed upon the cam shaft 37. The operation of said discharge finger is so timed that each succeeding can is pushed out of its recess 51', and, guided by the stationary finger 58, is deposited, in a horizontal position within the cylinder 59 of the can outlet valve. This can outlet valve is provided with a can inlet port 60, a can outlet port 60', and a pair of oppositely disposed sliding pistons 61 and 61', Figs. 1 and 11, said pistons being operated through connecting rods 62 and 62', by levers 63 and 63' fulcrumed at 64 and 64', and engaged by groove cams 65 and 65' mounted upon the cam shaft 37. Said can outlet or discharge valve operates when a can is present, in a manner essentially similar to that of the can inlet valve previously described. But it differs from said last named valve in that

provision is made for preventing the escape of steam through the valve in case no can comes out of the cooker.

One side of the cam 65', as shown particularly in Fig. 6, is straight for a portion 66 of its circumference, followed by a comparatively sudden offset 66'. The opposite side 67 of the groove is offset at a lesser angle, as shown. A spring 68, Fig. 1, normally holds the roller attached to the lever 63' against the straight side 66 until the sudden offset 66' is reached. Therefore, when no can is introduced into the valve from the discharge wheel 51, the piston 61' remains stationary until the opposite piston 61 approaches into contiguity therewith, as shown in Fig. 11, thereby forcing the steam contained between said pistons back into the barrel to prevent its loss and to save the operator the inconvenience of its escape into the room. Both pistons then move together, remaining in contiguity until the can inlet port 60 is closed by the piston 61, after which the remainder of the cycle is completed in the usual manner. If a can be interposed between said pistons, however, the initial movement of the piston 61 will force the can against the piston 61', and will thereby move said piston 61' against the tension of the spring 68, so that the roller carried by the lever 63' will follow approximately the side 67 of the cam groove. Both pistons will then move to the left, carrying the can between them until said can is in line with the can outlet port 60', whereupon the piston 61 will stop, and the piston 61' will be moved slightly farther, by the action of the portion 66' of the cam groove, to free the can. After the discharge of said can, the piston 61' closes up on the piston 61, and both move back together, finally separating to permit the entrance therebetween of another can.

To eject the can from the discharge valve, I provide a finger 69, Figs. 1 and 3, fulcrumed at 70, and provided at its lower end with a roller 71, Fig. 3, adapted to lie within a groove 72 in the reverse face of the cam member 57. Said finger ejects each can from between the pistons of the discharge valve, and forces said can out through the discharge port 60' into a discharge chute indicated at 73, from which it may be removed in any convenient manner.

The delivery of the cans from the can path rails 8 of the reel 6 is made positive, by means of the fixed finger 74, shown in Fig. 3. This finger projects into the cooking chamber 1, its inner end being so disposed relatively to the circular path of the reel, that as the rails 8 carry the cans up to their delivery communication with the discharge wheel shell 52, they successively meet with the finger 74 and are diverted from the rails and delivered into the pockets 51' of the discharge wheel 51. Their discharge from the

cooking chamber is thus not dependent on gravity but is positive, a requirement of value in a pressure cooker.

I claim:

1. A pressure cooker comprising a cooking chamber provided with openings for the reception and discharge of the can; means within the chamber to advance the can therethrough; valves to control the can openings of the chamber; and a movable finger to positively eject the can from said valves. 70

2. A pressure cooker comprising a cooking chamber provided with openings for the reception and discharge of the can; means within the chamber to advance the can therethrough; can-carrying wheels in fluid tight communication with the chamber openings; and valves to control the feed of the can to one of said wheels and its discharge from the other. 80

3. A pressure cooker comprising a cooking chamber provided with openings for the reception and discharge of the can; means within the chamber to advance the can therethrough; can-carrying wheels in fluid tight communication with the chamber openings; valves to control the feed of the can to one of said wheels and its discharge from the other; and means for positively feeding and ejecting the can from said valves. 90

4. A pressure cooker comprising a cooking chamber provided with openings for the reception and discharge of the can; means within the chamber to advance the can therethrough; can-carrying wheels in fluid tight communication with the chamber openings; valves to control the feed of the can to one of said wheels and its discharge from the other; and a movable finger operating in connection with said last named 100 wheel to positively discharge the can therefrom into the valve.

5. A pressure cooker comprising a cooking chamber provided with openings for the reception and discharge of the can; means within the chamber to advance the can therethrough; can-carrying wheels in fluid tight communication with the chamber openings; valves to control the feed of the can to one of said wheels and its discharge from the other; a movable finger operating in connection with said last named wheel to positively discharge the can therefrom into the valve; and a movable finger to positively eject the can from said valves. 110

6. A pressure cooker comprising a cooking chamber provided with an inlet and an outlet opening and having means within it to advance the can therethrough; an initial can-feed wheel; a valve in fluid tight communication with said feed wheel; and a second can-feed wheel in fluid tight communication with said valve and with the cooking chamber. 125

7. A pressure cooker comprising a cook- 130

ing chamber provided with an inlet and an outlet opening and having means within it to advance the can therethrough; a rotatable initial can-feed wheel; a fixed finger to eject the can from said wheel; a valve in fluid tight communication with said feed wheel; a movable finger to positively eject the can from said valve; and a second can-feed wheel in fluid tight communication with said valve 10 and with the cooking chamber.

8. A pressure cooker comprising a cooking chamber provided with openings for the reception and discharge of the can; means within said chamber to advance the can therethrough; valves to control the can openings of the chamber consisting of a cylinder having a port to receive the can and a separate port to deliver it, and a pair of independent opposing pistons in said cylinder having a movement both in unison and with relation to each other to receive and deliver the can and displace the steam between them and in all positions to close communication between the cylinder ports irrespective of the can; and a movable finger operating through the cylinder wall opposite its delivery port, to contact with and positively discharge the can through said port.

9. A pressure cooker comprising a cooking chamber provided with openings for the reception and discharge of the can; means within said chamber to advance the can therethrough; can-carrying wheels in fluid tight communication with the chamber openings; and valves in fluid tight communication with said wheels, consisting of a cylinder having a port to receive the can and a separate port to deliver it and a pair of independent opposing pistons in said cylinder having a movement both in unison and with relation to each other to receive and deliver the can and displace the steam between them and in all positions to close communication between the cylinder ports irrespective of the can.

10. A pressure cooker comprising a cooking chamber provided with openings for the reception and discharge of the can; means within said chamber to advance the can therethrough; can-carrying wheels in fluid tight communication with the chamber openings; valves in fluid tight communication with said wheels, consisting of a cylinder having a port to receive the can and a separate port to deliver it and a pair of independent opposing pistons in said cylinder having a movement both in unison and with relation to each other to receive and deliver the can and displace the steam between them and in all positions to close communication between the cylinder ports irrespective to the can; and a movable finger operating in the cylinder opposite its delivery port, to

contact with and positively discharge the can through said port.

11. A pressure cooker comprising a cooking chamber provided with a can inlet and a can outlet; means within the chamber to advance the can from the inlet to the outlet; and a valve to control the outlet consisting of a cylinder having a port in communication with the outlet to receive the can therefrom, and a second port to discharge the can, a pair of independent opposing pistons in said cylinder having a movement both in unison and with relation to each other to receive and deliver the can and in all positions to close communication between the cylinder ports irrespective of the can, and means operating when no can is delivered between the pistons, to effect their approach and thereby drive back the steam into the chamber.

12. A pressure cooker comprising a cooking chamber provided with a can inlet and a can outlet; means within the chamber to advance the can from the inlet to the outlet; a can discharge wheel in fluid tight communication with the chamber outlet to receive the can therefrom; a valve in fluid tight connection with the can-discharge wheel, consisting of a cylinder having a port to receive the can from the wheel and a delivery port for said can and a pair of independent opposing pistons in said cylinder to advance the can therethrough in all positions closing communication between the cylinder ports irrespective of the can; and means operating when no can is delivered between the pistons, to effect their approach and thereby drive back the steam into the chamber.

13. A pressure cooker comprising a cooking chamber provided with a can inlet and a can outlet; means within the chamber to advance the can from the inlet to the outlet; a can discharge wheel in fluid tight communication with the chamber outlet to receive the can therefrom; a valve in fluid tight connection with the can-discharge wheel, consisting of a cylinder having a port to receive the can from the wheel and a delivery port for said can and a pair of independent opposing pistons in said cylinder to advance the can therethrough in all positions closing communication between the cylinder ports irrespective of the can; means operating when no can is delivered between the pistons, to effect their approach and thereby drive back the steam into the chamber; and a movable finger in juxtaposition to the can-discharge wheel to positively force therefrom the can when present into the inlet port of the valve cylinder.

14. A pressure cooker comprising a cooking chamber provided with a can inlet and a can outlet; means within the chamber to

advance the can from the inlet to the outlet; a can discharge wheel in fluid tight communication with the chamber outlet to receive the can therefrom; a valve in fluid tight connection with the can-discharge wheel, consisting of a cylinder having a port to receive the can from the wheel and a delivery port for said can and a pair of independent opposing pistons in said cylinder to advance the can therethrough in all positions closing communication between the cylinder ports irrespective of the can; means operating when no can is delivered between the pistons, to effect their approach and thereby drive back the steam into the chamber; a movable finger in juxtaposition to the can-discharge wheel to positively force therefrom the can when present into the inlet port of the valve cylinder; and a movable finger operating through the wall of the valve cylinder opposite its outlet port to positively force the can therefrom.

15. In a pressure cooker, the combination with rotating can-carrying members of the can path within the cooking chamber, and means for receiving the cans therefrom, of a fixed finger contiguous to said can carrying members and adapted to positively divert the cans therefrom into the receiving 30 means.

16. In a pressure cooker, the combination of a cooking chamber; a can path within the chamber comprising a rotating series of can carrying rails; an exterior shell in communication with the cooking chamber to receive the cans therefrom; a discharge wheel within said shell; and a fixed finger contiguous to said can carrying rails to positively divert the cans therefrom to the discharge 40 wheel.

17. In a pressure cooker, the combination of a cooking chamber; a can path within the chamber comprising a rotating series of can carrying rails; an exterior shell in communication with the cooking chamber to receive the cans therefrom; a discharge wheel 45

within said shell; a fixed finger contiguous to said can carrying rails to positively divert the cans therefrom to the discharge wheel; a discharge valve in communication with the shell; and a movable finger to positively force the can from the discharge wheel into the valve.

18. In a pressure cooker, the combination of a cooking chamber; a can path within the chamber comprising a rotating series of can carrying rails; an exterior shell in communication with the cooking chamber to receive the cans therefrom; a discharge wheel within said shell; a fixed finger contiguous to said can carrying rails to positively divert the cans therefrom to the discharge wheel; a discharge valve in communication with the shell; a movable finger to positively force the can from the discharge wheel into the valve; and a movable finger to positively discharge the can from the valve.

19. A pressure cooker comprising a cooking chamber provided with openings for the reception and discharge of the can; means within the chamber to advance the can therethrough; valves to control the can openings of the chamber; and means for positively feeding the can to said valves and 75 ejecting it therefrom.

20. A pressure cooker comprising a cooking chamber provided with openings for the reception and discharge of the can; means within the chamber to advance the can therethrough; valves to control the can openings of the chamber; and suitable fingers operating on the can to positively feed it to said valves and to eject it therefrom.

In testimony whereof I have signed my name to this specification in the presence of two subscribing witnesses.

ALBERT R. THOMPSON.
